UNITED STATES PATENT OFFICE

2,485,139

SHOVEL LOADING MACHINE

Gilbert E. Coats, Fort Dodge, Iowa

Application April 23, 1947, Serial No. 743,286

3 Claims. (Cl. 214—139)

1

This invention relates generally to loading machines and in particular to a tractor mounted loader attachment for handling manure, hay, dirt and the like.

An object of this invention is to provide an improved loading machine.

A further object of this invention is to provide a tractor mounted loader attachment having a pivoted lift frame located forwardly of the tractor operator's seat, in which a load carrying unit is maintained in a near level or horizontal position at all moved positions of the lift frame.

Another object of this invention is to provide a tractor loader attachment in which the lift arms are of a relatively short overall length and assembled with a load carrying unit such that the unit is maintained in a near level position at all moved positions of the lift arms.

A further object of this invention is to provide a tractor loader attachment having a pair of lift arms pivoted on an upright frame, in which a bucking force, during a scoop loading operation, is applied to the tractor frame so that the lift arms and upright frame are relieved of such force.

Still another object of this invention is to provide a tractor loader attachment which is of a compact and rugged construction, readily assembled with and removed from a tractor, adapted to be mounted forwardly of the tractor operator's seat and of a height to afford the operator full visibility in the operation of the tractor and loader.

A feature of this invention is found in the provision of a tractor mounted loader attachment in which a pair of pivoted lift arms are pivoted at their rear ends on an upright frame, located forwardly of the tractor operator's seat, for up and down pivotal movement. Disposed above the lift arms are a pair of stabilizing arms which are pivoted on the upright frame, and movably connected with a scoop, carried between the free ends of the lift arms, through a pivoted frame structure such that the scoop, on being elevated, is progressively tipped forwardly and downwardly relative to the lift arms, so as to always be in a substantially horizontal position.

Another feature of this invention is found in the provision of a loading machine having an upright frame for pivotally supporting the rear end of a lift frame, in which the front end of the lift frame is engageable with the main frame of the machine, in a lowered position of the lift frame, whereby any bucking force applied on the lift frame is transmitted to the main frame.

2

Yet a further feature of this invention is found in the provision of a loader attachment for a tractor, in which a main horizontal frame is positionable about the tractor frame and secured thereto. The front portion of the main frame projects forwardly of the tractor frame and carries an upright frame which has a top section supported for up and down movement. The top section is moved by a hydraulic cylinder carried on the projected main frame portion, with such movement in an upward direction being limited by coacting stop means on the top section and the base of the upright frame. A pair of pivoted lift arms, arranged at opposite sides of the tractor frame, are connected by cables with the top section so as to be lowered and raised in response to an operation of the hydraulic cylinder.

Further objects, features and advantages of this invention will become apparent from the following description when taken in connection with the accompanying drawings, in which:

Fig. 1 is a side elevational view of a usual type farm tractor shown in assembly relation with the loader attachment of this invention; with parts of the tractor being removed to more clearly show this assembly;

Fig. 2 is an enlarged sectional view taken on the line 2—2 in Fig. 1;

Fig. 3 is a fragmentary perspective view of the front end of the lift frame, with the scoop being removed so as to show the relative assembly of the lift frame with the scoop stabilizing structure;

Fig. 4 is a plan view of the tractor and loader assembly shown in Fig. 1;

Fig. 5 is an enlarged sectional detail view of the scoop latch mechanism, as seen along the line 5—5 in Fig. 4;

Fig. 6 is a sectional detail view of the lift mechanism taken on the line 6—6 in Fig. 2; and

Fig. 7 is a sectional detail view as seen on the line 7—7 in Fig. 2.

With reference to the drawings, the loader attachment of this invention is illustrated in Figs. 1 and 4 in assembly relation with a usual type farm tractor having a main frame 10, a rear axle housing 11, traction wheels 12, front steering wheels 13, and an engine 14 equipped with an oil pump unit indicated at 16.

The loader attachment comprises a main horizontal frame 17, having a pair of longitudinal frame members 18 arranged at opposite sides of the tractor frame 10 which are secured at their rear ends 19 to the rear axle housing 11 (Figs. 1 and 4). The frame members 18, adjacent their

front ends, are secured to the tractor, as indicated at 21, and project forwardly ahead of the tractor. A transverse brace member 22 (Fig. 2) located forwardly of the tractor, is connected between the front ends of the frame members 18.

Mounted on the loader main frame at a position intermediate the wheels 12 and 13 and forwardly of the tractor operator's seat 23, is a rear upright frame 24 (Figs. 1 and 4) comprised of a pair of upright angle members 26 arranged at opposite sides of the tractor frame 10 and secured at their lower ends to the frame members 18. A brace member 27 connects the upright angle members 26 at a position spaced from their upper ends, with the frame 24 being supported against tilting movement by forwardly and downwardly inclined braces 28 secured at their lower ends to the frame members 18.

A load carrying unit or scoop 29 is pivotally supported at 31 between the front ends of a pair of lift arms 32 and 32a which are arranged at opposite sides of the tractor and have their rear ends pivoted at 33 to the upright angle members 26. The lift arms 32 form part of a pivoted lift frame and are provided with forward extensions 30 and 30a. A transverse brace member 34, connected between the front ends of the lift arms 32 and 32a, extends laterally outwardly from the lift arms, and the lift arm extensions 30 and 30a are secured at their rear ends to opposite ends of the connecting member 34 and project forwardly in a parallel relation with the arms 32. It is seen, therefore, that the lift arm extensions 30 and 30a are offset laterally outwardly from the arms 32 and 32a, respectively.

As best appears in Fig. 3, the lift arms 32 and 32a and connecting member 34 are of a pipe or tube construction, while the extensions 30 and 30a are of an angle construction. Gusset plates 36 are welded between the arms 32 and 32a and the laterally projected ends of the connecting member 34. The scoop 29 is of a width substantially equal to the distance between the lift arm extensions 30 and 30a and in its supported position on the pivots 31 is located forwardly of the connecting member 34.

By virtue of the pivoted support of the lift arms 32 and 32a on the upright frame 24, at a position forwardly of the tractor operator's seat 23, the lift arms are of a relatively short length. As a result, if the scoop 29 was held against movement relative to the lift arms, on elevation of the lift arms it would be tilted rearwardly at an angle such that a large portion of the material carried in the scoop would be dumped rearwardly over the tractor front end, prior to any dumping movement of the scoop. In order to prevent such an occurrence, and to hold the scoop 29 in a load-holding or near level position during its movement to a dump position, there is provided a scoop stabilizing mechanism which includes a pair of stabilizing arms 37 (Figs. 1 and 4) which are arranged at opposite sides of the tractor and have their rear ends pivoted at 38 to the upper ends of the angles 26 of the rear upright frame 24. The pivots 38 are thus arranged above the pivots 33 for the rear ends of the lift arms 32 and 32a.

The stabilizing arms 37 extend forwardly and downwardly from the rear upright frame 24, at positions above the lift arms 32 and 32a and have adjustable forward sections 39 which have their front ends pivoted at 41 to the upper ends of a pair of transversely spaced uprights 42 which form part of a pivoted frame structure 43 (Fig.

3). The uprights 42 are of a bar construction and are connected together adjacent their lower ends by a pair of vertically spaced transverse angle members 44 and 46. A brace plate 47 is secured, 5 as by welding, between the angle members 44 and 46.

Each upright 42 is provided at its lower end with a forward extension 48, which has a brace member 49 connected between its front end and 10 an upright 42. The front ends of the extensions 48 are pivoted on the pivots 31 for the scoop 29.

It is seen, therefore, that the frame 43 has a 15 rear upright section, comprised of the angle members 44 and 46, and the uprights 42, which is arranged between the rear wall 60 of the scoop 29 and the connecting member 34, and forward extensions 48, of a flat bar construction, arranged in a straddling relation with the scoop 29 and pivoted at their front ends on the scoop pivots 20 31. The frame 43 is thus pivotally connected between the front extensions 30 and 30a of the lift arms 32 and 32a and the front adjustable extensions 38 of the stabilizing arms 37. The stabilizing arms 37 are of a tubular construction, and 25 telescopically receive their extensions 39 which are also of a tubular construction. The extensions 39 are held in an adjusted position by the provision of lock or friction screws 51 threadable within the stabilizing arms 37 for bearing engagement against the extensions 39.

The latch mechanism for the scoop 29 (Figs. 3 and 5) is carried on the pivoted frame 43 and includes a rock shaft 52 rockably supported in 35 bearings 53 mounted on the top side of the upper angle 46 in the pivoted frame 43. The rock shaft 52 extends over approximately one-half of the length of the upper angle 46 and is integrally formed at its inner end with an upright rock arm 54, the free end of which is loosely received in an 40 elongated slot 56 formed in a rear extension 57 on the upper end of a latch member 58. The lower end of the latch member 58 is pivotally supported at 59 on the upper angle 46 and is formed intermediate its ends with an upright elongated slot 61 for releasably engaging a stop member 62 on the scoop back wall 60.

The rock shaft 52 is biased in a counter-clockwise direction, as viewed in Fig. 3, to maintain the 50 latch 58 in an engaging position with the catch or stop 62 by the provision of a coil spring 63 connected between a rock arm 64, at the outer end of the shaft 52 and a brace member 49.

The free end of the rock arm 64 is pivotally 55 connected to the forward end of an actuating lever 66 (Figs. 1 and 3) which extends upwardly and rearwardly for slidably support of its rear end in the upright frame 24. A hand grip 67, integral with the lever 66, is arranged rearwardly of the 60 upright frame 24, at a position conveniently accessible to the tractor operator.

In the operation of the stabilizing mechanism, as the lift arms 32 and 32a are elevated, the scoop 29, by virtue of its connection with the pivoted frame 43 through the latch mechanism on the upper angle 46, is progressively tipped forwardly by the pivoted action of the stabilizing arms 37. Stated otherwise, as the lift arms 32 and 32a are elevated from their full line position in Fig. 1, to their dotted line position indicated at A, the pivoted frame 43, as viewed in Fig. 1, is pivotally moved in a clockwise direction and forwardly relative to the lift arms, to in turn provide for a progressive forward tilting movement of the scoop 70 29. As also shown in dotted lines at B in Fig. 1,

for an intermediate or horizontal position of the lift arms, at which the scoop 29 is elevated above the tractor, the scoop 29 is more level than its dump position. However, the scoop 29 is maintained in a near level position at substantially all moved positions of the lift arms, so as to eliminate any of the load being dropped therefrom prior to a dumping operation.

On elevation of the lift arms 32 and 32a to their raised position, illustrated in dotted lines at A in Fig. 1, the scoop 29 is dumped by pulling rearwardly on the lever 66 whereby the latch 58 is pulled out of engagement with the catch 62.

The hoisting mechanism for raising and lowering the arms includes a front upright frame 68 (Fig. 2) which has a bottom section comprised of a pair of oppositely arranged upright channel members 69 and 69a secured at their lower ends to opposite ends of the front transverse member 22 of the loader main frame. The channel members 69 and 69a are faced outwardly and are adapted to receive therein upright tubular members 71 which are welded to the channel members 69 and 69a.

A top section for the upright frame includes a transverse head member 70 of a hollow construction, having a pair of downwardly extended tubular members 72 which are slidably receivable within the upright tubular members 71 of the bottom section. Rotatably supported in the head member 70 are pairs of oppositely arranged pulleys 73 and 73a and 74 and 74a (Figs. 2 and 6), with the pulleys 73 and 73a being arranged in a common plane rearwardly of a common plane for the pulleys 74 and 74a. Further, each pair of adjacent pulleys 73 and 74, and 73a and 74a are arranged at opposite sides of a slidable tube member 72.

A cable 76 is attached at one end 78 to the channel member 69a and extends upwardly for travel over the pulley 74a, longitudinally of the head member 70 for travel about the pulley 74 and then downwardly for connection of its opposite end 79 with the lifting arm 32. A second cable 81 is attached at its end 82 to the upright channel 69 and extends upwardly for travel over the pulley 73, longitudinally of the head member 70 for passage over the pulley 73a and then downwardly for the connection of its opposite end 84 with the lift arm 32a. The cables 76 and 81, by virtue of the offset relation of the pulleys 73 and 73a relative to the pulleys 74 and 74a, are thus in a clearance relation within the head member 70. Guide rollers 86 carried at opposite ends of the head member 70, serve to maintain the cables 76 and 81 within the pulleys 73a and 74, respectively, at all moved positions of the lift arms.

The cables 76 and 81 are raised and lowered by the provision of an upright hydraulic cylinder 89 mounted at a central position on the transverse connecting member 22 and having a piston 91 connected at 92 with the head member 70. Fluid under pressure is supplied to the cylinder through a conduit 93 connected with the tractor-operated pump unit 16.

On raising of the piston 91 the cables 76 and 81 are concurrently lengthened between their attached ends 78 and 82 and the pulleys 74a and 73, respectively, and decreased in length between their attached ends 79 and 84 and the pulleys 74 and 73a, so that a balanced lifting action is applied on the lift arms 32 and 32a.

The upward movement of the head member 70 is limited by the provision of means including rod members 94 extended upwardly in a coaxial rela-

tion within the upright tubes 71 (Fig. 2). The lower ends of the rods 94 are mounted on bottom cover members 96 for the upright tubes 71. The rod members 94 are slidably extended through cap members 98 provided at the lower ends of the slidable tubes 72, which cap members are engageable with stop members 97 at the upper ends of the rods 94 to define an uppermost position of the head member 70. On a lowering of the head member 70, the rods 94 extend upwardly within the slidable tubes 72.

Carried at the forward ends of the frame members 18 are a pair of hook members 99 (Figs. 2 and 7) which have their hook portions 101 opened upwardly and extended in a forward direction. When the scoop 29 is in its lowered position, illustrated in full lines in Fig. 1, the transverse connecting member 34, between the lift arms 32 and 32a, is received within the hook portions 101. Thus on the application of a bucking force on the scoop 29, when the scoop is being loaded, this force is transmitted through the lift arm extensions 30 and connecting member 34 against the hooks 99 and through the frame members 18 to the tractor frame 10.

As a result, the lift arms 32 and 32a and the upright frame 24 are substantially free of the bucking force impact. The frame 24 is thus subjected only to the load carried in the scoop 29 during its elevation from its full line position to its dotted line position A, illustrated in Fig. 1.

The dumping movement of the scoop 29, on release of the latch 58, is limited by the provision of a coil spring 102 (Fig. 1) connected at its upper end to a forward extension 103 on the head member 70 and at its lower end to a chain 104 which extends downwardly about a pulley 106 mounted on the upper angle 46 for connection at 107 with the rear wall 60 of the scoop 29.

From a consideration of the above description it is seen that the invention provides a tractor loader attachment adapted to be readily assembled with and removed from a tractor, applicable to tractors with short wheel bases, and efficient in operation to raise a load to a relatively high elevation, while maintaining the scoop in a substantially near level position. The attachment is of a compact design and does not in any way interfere with a normal storage of the tractor in a machine shed or with the visibility of the tractor operator in the maneuverability of the tractor and operation of the loader.

Although the invention has been described with respect to a preferred embodiment thereof, it is to be understood that it is not to be so limited since changes can be made therein which are within the full intended scope of this invention, as defined by the appended claims.

I claim:

1. A loading machine including a portable frame, an upright frame on said portable frame, a pair of lift arms arranged at opposite sides of said portable frame having their rear ends pivoted on said upright frame, a pair of stabilizing arms arranged at opposite sides of said portable frame at positions above said lift arms and pivoted at their rear ends on said upright frame, a load carrying unit, pivot means for supporting said load carrying unit between the front ends of said lift arms, a pivoted frame including an upright portion located rearwardly of said load carrying unit and pivoted at its upper end with the front ends of said stabilizing arms, forward extensions on said upright portion arranged to opposite sides of said load carrying unit and pivoted at their front ends on said pivot means

for the load carrying unit, a latch mechanism for said load carrying unit mounted on said upright portion, and means for raising and lowering said lift arms.

2. A loading attachment for a tractor having a frame comprising, a main horizontal frame adapted to be secured to said tractor frame and including a front portion extended forwardly from said tractor frame, forwardly projected hook members on said front portion, an upright frame on said main frame, a lift frame having its rear end pivoted on said upright frame, a transverse brace member adjacent the front end of said lift frame at a position so as to be received within said hook members when the lift frame is in a lowered position, and means for raising and lowering said lift frame.

3. In a loading machine having a main frame and a lift frame pivoted at its rear end on said main frame, an upright frame mounted on the front end of said main frame including a bottom section having a pair of upright tubular members spaced transversely of said main frame, rod members coaxially extended within said upright members, stop members on said rod members at positions spaced upwardly from the lower ends of said upright tubular members, a movable top section including a head member having downwardly extended tubular movable members movably supported within said

5
